UNITED STATES PATENT OFFICE.

ALEXANDER KARSH, OF NEW YORK, N. Y.

DESIGN FOR A STAND FOR SILVERWARE OR SIMILAR ARTICLE.

Application filed July 5, 1923. Serial No. 6,676. Term of patent 3½ years.

To all whom it may concern:

Be it known that ALEXANDER KARSH, a citizen of the United States, and resident of the city of New York, in the county of New York and State of New York, has invented a new, original, and ornamental Design for Stand for Silverware or Similar Article, of which the following is a specification, reference being had to the accompanying drawing, forming part thereof, in which—

The figure is a perspective view of a stand embodying my new design.

I claim:

The ornamental design for a stand for silverware or similar article as shown.

Signed at New York city, in the county of New York and State of New York, this 3rd day of July, 1923.

ALEXANDER KARSH.
